United States Patent Office

Des. 227,426

Patented June 26, 1973

227,426

END FRAME FOR A CRIB

Allen D. Jacobs, Los Angeles, Calif., assignor to
Questor Corporation, Toledo, Ohio

Filed Mar. 21, 1972, Ser. No. 236,800

Term of patent 14 years

Int. Cl. D6—06

U.S. Cl. D6—14

FIG. 1

FIG. 2

FIG. 3

FIG. 4

FIG. 1 is a front elevational view of an end frame for a crib, showing my new design;

FIG. 2 is a right side elevational view;

FIG. 3 is a top plan view; and

FIG. 4 is a rear elevational view.

I claim:

The ornamental design for an end frame for a crib, as shown.
